UNITED STATES PATENT OFFICE.

JOHN H. SCHMITT, OF EMPORIA, KANSAS.

SAFETY-RAZOR.

1,210,006.

Specification of Letters Patent. Patented Dec. 26, 1916.

Application filed September 1, 1916. Serial No. 118,670.

To all whom it may concern:

Be it known that I, JOHN H. SCHMITT, a citizen of the United States, residing at Emporia, in the county of Lyon and State of Kansas, have invented certain new and useful Improvements in Safety-Razors; and I do declare the following to be a full, clear, and exact description of the invention, such as will enable others skilled in the art to 10 which it appertains to make and use the same.

This invention relates to improvements in safety razors, the principal object being to provide a simply constructed, cheap yet efficient frame or holder for the improved blade.

An additional object is to provide a device of this character provided with a blade which is curved transversely to the cutting edge in order that the full length of said edge will be effective when the device is in operation.

Still another object is to provide a method for constructing the blade holder and handle 25 of a single piece of wire.

With the above and many other objects in view, the invention resides in the novel features of construction, combination and arrangement of parts which will be herein- 30 after particularly described and claimed.

In the accompanying drawing, Figure 1 represents a side elevation of a safety razor constructed in accordance with my invention; Fig. 2 is a plan view; Fig. 3 is a front elevation of the blade in operative position; Fig. 4 is a transverse section on the plane of the line 4-4 of Fig. 1; Fig. 5 is a longitudinal section on the plane of the line 5-5 of Fig. 2; and Fig. 6 is a horizontal section 40 on the plane of the line 6-6 of Fig. 3.

In the drawing wherein similar reference characters indicate like parts throughout the several views, 1 denotes an ordinary razor blade preferably provided with only one cutting edge, said blade being held in a suitable frame constructed of a single piece of wire, as will be hereinafter more particularly set forth. In a majority of safety razors now on the market the cutting blade 50 is flat and therefore except in a very few places on the face only a portion of the blade is operative. By providing a frame which causes the blade to be curved transversely to the cutting edge I have overcome 55 this difficulty and the cutting edge will fit

the curves of the face and therefore cut on its entire length.

The frame in which the blade 1 is disposed consists broadly of two parts, namely, the holder designated by the numeral 2 and the 60 guard 3. Both of these parts are preferably formed of the same piece of wire in order that the device may be inexpensively constructed. In forming the frame a wire of suitable length is used, the intermediate portion thereof forming the guard 3, said guard being slightly curved to conform to the curvature of the face. When this guard has been formed into the proper shape, the ends of the wire are bent inwardly toward each other as shown at 4 for a short distance and then bent laterally away from the guard 3 and substantially at right angles thereto to provide a pair of gripping fingers 5, these fingers being disposed in engagement with 70 the upper rear face of the cutting blade when the latter is in position. The ends of the wire are then bent upon the fingers 5, or toward the guard 3, to provide an additional pair of gripping fingers 6 which co- 75 act with the fingers 5 to hold the blade therebetween as clearly shown in Fig. 1. The ends of the wire are next bent laterally inwardly toward each other as at 7 and then upwardly away from the guard 3 to produce a third pair of fingers 8, this pair of fingers and also the portions 7 being disposed on the outer face of the blade. For coöperation with these fingers 3, the wires are again bent toward the guard 3 to form 80 a fourth pair of gripping fingers 9.

From the foregoing description and an examination of the drawings it will be seen that the fingers 5 and 6 coact together to grip the blade 1 at its outer edges, the fingers 8 and 9 coacting and gripping the blade at its intermediate portion, the side edges of the blade remote from its cutting edge resting in the seats formed at the junction of the fingers.

The outer portions of the guard 3 and the adjacent parts 4 are bent outwardly as shown at 10, these parts 10 being disposed beyond the side edges of the blade 1 and in engagement therewith so as to prevent longitudinal shifting of the latter. The gripping action of the fingers 6 and 8 forces the intermediate portion of the blade 1 inwardly toward the other fingers and against the portion 7, thereby curving the blade 110

slightly so that it conforms to the curvature of the face.

The frame as described may be suitably connected with any desired form of handle, 5 and is preferably connected to a handle formed of the same wire of which it is itself constructed. The ends of the wire after forming the fingers 9 are bent in planes at substantially right angles to the plane 10 of the guard 3 and then upwardly parallel to the fingers 9, thus forming a pair of substantially U-shaped springs 12. The ends of the wire after forming these springs 12 are connected to the wire handle or other 15 handle which may be used.

In the present instance, one end of the wire is extended laterally from the frame as shown at 13 and the other end of the wire is coiled around this portion 13 as 20 shown at 14. In other words, the portion 13 extends along the entire length of the handle within the coils formed by the end 14. This forms a very simple handle, while 25 because of the convolutions the fingers of the user of the safety razor will not slip thereon.

The blade 1 may be readily placed in the frame or removed therefrom because of the 30 spring action of the fingers. Once within the frame, however, the blade will be held 35 against accidental shifting and will remain in its curved position which corresponds to the curvature of the guard 3. Because of its extreme simplicity the razor frame and handle constructed as hereinbefore de-

scribed may be manufactured very cheaply and marketed at a low cost.

I claim:

In a device of the class described, a razor blade frame constructed of a single piece 40 of wire, the intermediate portion of said wire forming a guard, the ends of said wire being bent inwardly toward each other and then upwardly at right angles to said guard 45 to form a pair of gripping fingers, then downwardly toward said guard to provide an additional pair of gripping fingers for coaction with the first pair, the ends of wire being bent laterally inwardly toward each other and then upwardly away from the 50 guard and substantially parallel to the first mentioned pairs of fingers to form a third pair of gripping fingers then downwardly toward the guard to provide a fourth pair of fingers for coaction with the third pair, the ends of the wire being bent laterally 55 away from the last mentioned pair of fingers and then upwardly substantially parallel thereto to provide a pair of U-shaped springs, a handle connected to the ends of 60 said springs, and a razor blade held in said frame by said gripping fingers.

In testimony whereof I have hereunto set my hand in the presence of two subscribing witnesses.

JOHN H. SCHMITT.
